UNITED STATES PATENT OFFICE

91,945

DESIGN FOR A TOY

Ferris J. Khouri, Moira, N. Y.

Application December 21, 1933, Serial No. 50,175

Term of patent 3½ years

To all whom it may concern:

Be it known that I, FERRIS J. KHOURI, a citizen of the United States, residing at Moira, in the county of Franklin, and State of New York, have invented a new, original, and ornamental Design for a Toy, of which the following is a specification, reference being had to the accompanying drawing, forming part thereof.

I claim:

The ornamental design for a toy, as shown and

FERRIS J. KHOURI.
